UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

SCORING MACHINE

Application filed May 31, 1928. Serial No. 281,639.

My invention relates in general to scoring machines and more particularly to an improved machine for die-scoring the ends of containers and the like by means of rollers.

5 A principal object of my invention is the provision of an improved scoring roller in such a machine which has projecting from its cylindrical face a die or dies of the exact dimension, pattern and configuration of the 10 score to be produced upon the can end.

Another important object of the invention is the provision of an improved scoring roller which not only positively advances a can end to be scored in a straight line of 15 travel, but also scores the same simultaneously with the feeding of it by starting the score at a point or line inwardly of the can end flange and progressively spreading the score in two directions and gradually returning the two resulting score lines to meet each 20 other and form an endless score line defining a tear-away area of any desired shape, pattern and dimension.

Another important object of the invention 25 is the provision of an improved scoring roller which is journaled in spring-pressed sliding bearings and which cooperates with a second or backing roller to impress upon a can end passing between the rollers a complete figure or pattern score of proper and 30 uniform depth, irrespective of the thickness of the metal of the can end.

Still another important object of the invention 35 is the provision of a die scoring machine which is of simple construction and speedy operation, and which is adapted to produce scorings of any desired configuration or pattern on a variety of different shaped can ends, such as circular can ends, 40 elliptical can ends, oblong can ends with rounded corners, square and rectangular can ends, and other shapes, by merely changing the shape and dimension of the die part of the scoring roller to the shape and dimension 45 of the scoring desired. It will be manifest as the invention is better understood that it is capable of use in the manufacture of articles other than those mentioned.

Another important object of my invention 50 is the provision of a machine of the char-

acter described wherein positive and accurate feed of the can ends will be assured and the parts protected from damage in their operation.

Numerous other objects and advantages of 55 the invention will be apparent as it is better understood from the following description, which, taken in connection with the accompanying drawings, discloses a preferred embodiment thereof.

Referring to the drawings:

Figure 1 is an end elevation of my scoring machine taken from the side on which the scoring roller is mounted;

Fig. 2 is a side elevation taken from the 65 left hand side of Figure 1, small parts of the rollers being broken away to more clearly illustrate the cooperation of the scoring roller and backing roller and to show the 70 beginning of a scoring operation;

Fig. 3 is an elevational view, similar to Figure 1 and partly in section, but with the scoring mechanism removed and showing the 75 backing roller and a can end held by the retarding jaws preparatory to being gripped and advanced by the scoring roller, and

Fig. 4 is a detailed section through the 80 gravity chute, taken along line 4-4 of Figure 1.

The machine embodying my invention is 85 preferably constructed as follows: A base 11 is provided which supports an upper frame 12, which has integral flanges 13 and 14 secured to the base 11 by bolt and nut connections 15. Viewing Fig. 2, the upper frame 16 may, for the sake of convenience of description, be divided into a left frame part 16 and a right frame part 17. The left frame part 16 includes bearing supports 18 and 19, which provide bearings for a shaft 20 on which is 90 mounted a backing roller 21. The right frame part 17 includes slide supports 22 and 23 for sliding bearing blocks 24 and 25, which have dove-tailed sliding connections 26 and 27 with the slide supports 22 and 23. The 95 sliding blocks 24 and 25 provide bearings for a shaft 28 on which is mounted the scoring and feeding roller 29.

One end of the shaft 28 carries a drive 100 pulley 30 which may be connected with any

suitable source of power (not shown) for continuous rotation of the shaft 28 and thereby of the scoring and feeding roller 29 when the machine is in operation.

- 5 The scoring roller 29 has projecting from its cylindrical smooth face 31 a die base or shoulder 32 upon which is mounted a scoring die 33. The die base 32 is of a dimension and configuration to exactly fit within the shoulder and sunken panel of a completely formed can end, the top of which is to be scored. The scoring die 33 is of a dimension and configuration exactly that of the score to be produced upon the can end. The configuration of the 10 scoring die 33 and the die base 32, shown in the preferred illustration of my invention, is elliptical because the can end shown in the drawings happens to be elliptical, but as pointed out in the preamble of this specification 15 the scoring die and die base may take any desired shape and may be made of any desired dimension according to the shape and dimension of the can end and the score to be produced thereupon.
- 20 The two sliding bearing blocks 24 and 25 are spring-pressed toward the backing roller 21 by means of springs 34, which have their ends engaging recesses 35 and 36 in the sliding blocks 24 and 25 and upright brackets 37, 25 respectively, which latter are secured to the slide supports 22 and 23 by screws 38. The function of the springs 34 is to provide a scoring pressure of yielding character upon the can end as it passes between the rollers 21 and 29. This spring presses the sliding bearing blocks 24 and 25 against limiting abutments 25' extending up from supports 22 and 23.
- 25 The left frame part 16 is formed with an upward extension or bracket 39, which supports the feeding mechanism now to be described.

30 This feeding mechanism includes a gravity chute which comprises a pair of vertical chute frames 40 secured to the bracket 39 by means of screws 41. Each of these vertical chute frames 40 is recessed or provided with guide-ways 42. The frames 40 are spaced apart from each other a distance equal to 35 the greatest width of the can end 43 to be scored so as to permit the latter to freely slide through said guide-ways 42 by gravity.

35 In order to further guide and support the longitudinal center of the can end 43, vertical center guide rods 44 and 45 are provided and are secured at 46 to a transverse frame member 47, which in turn is secured by screws 48 to the uprights 40.

40 The two side wing extensions of the bracket 39 have pivotally secured thereto, by means of pivot screws 49, lever arms 50 which terminate into inwardly extending, oppositely arranged retarding jaws 51 having contacting faces 52, conforming with the contour of

a can end 43 to be engaged around its periphery.

45 About midway between its pivotal connection and jaw termination, each lever arm 50 is provided with an ear 53 which is engaged by one end of a tension spring 54, which has its other end secured in a second ear 55 on the upright 40. Just below the spring connections, the lever arms 50 have bearings 56 for set screws 57 which are adapted to regulate and determine the exact distance the retarding jaws 51 are to be pulled inwardly by the springs 54 to properly grip the periphery of the can end 43 and retard its gravity travel.

50 The operation of the machine is as follows: 80 Can ends 43 are fed lengthwise into the gravity chute guide-ways 42, one at a time. The lowermost end in the stack or chute assumes the position shown in Fig. 3, that is to say, its downward travel is retarded by jaws 85 51 until the die base 32 and the die 33 upon the revolving roller 29 enter the sunken panel of the can end 43, and the die base 32, which snugly fits within the panel, engages the inner shoulder 58 which defines the sunken 90 panel and propels the can end downwardly between the scoring and feeding roller 29 and the backing roller 21, pulling the can end through the retarding jaws 51 against the tension of the springs 54.

55 Simultaneously with the positive feeding of the can end by the scoring roller, a score 95 59 of the exact dimension and shape of the die 33 is impressed upon the metal of the sunken panel of the can end. The score is 100 started at a point or line inwardly of the shoulder 58 and is progressively spread in 105 two directions gradually returning the two score lines to meet each other opposite the starting point to form an endless score line 110 which defines a tear-away area of the dimension and form desired. When the score 59 has been completely impressed upon the can 115 end 43, the latter is released from the rollers and falls by gravity through an opening in 120 the upper frame and base of the machine for 125 subsequent disposition.

56 It will be noticed that in the preferred illustration shown on the drawings, the scoring roller 29 is provided with two dies 33 upon its cylindrical face, which means that two can ends will be scored in the course of one revolution of the shaft 28 and the scoring roller 29. It is obvious, however, that any 130 number of die parts within certain limits can be formed on the surface of the scoring and feeding roller 29, such number depending upon the relative size of the scoring roller and the can end.

60 It is thought that the invention and many 125 of its attendant advantages will be understood from the foregoing description, and it will be apparent that various changes may be made in the form, construction and arrangement of the parts without departing from the 130

spirit and scope of the invention or sacrificing all of its material advantages, the form hereinbefore described being merely a preferred embodiment thereof.

5 I claim:

1. In a can end scoring machine, a scoring roller having upon its face a die member of the exact shape and dimension of the score to be produced upon and of the part to be removed from a can end, and means for feeding can ends past said roller in a straight line of travel.

2. In a can end scoring machine, a scoring roller having upon its cylindrical face a die member of the exact shape and dimension of the score to be produced upon a can end, said roller also having means for positively advancing said can end in a straight line of travel while the scoring operation takes place.

20 3. In a can end scoring machine, in combination, a scoring and feeding roller having a scoring edge defining the outline of the part to be removed from the can end, a backing roller, and a gravity feed for feeding can ends successively to said rollers.

25 4. In a can end scoring machine, in combination, a scoring and feeding roller, a backing roller, a gravity feed for feeding can ends successively to said rollers, and means for retarding each can end until it is positively engaged and advanced by said feeding and scoring roller.

30 5. In a can end scoring machine, a scoring roller having a die member upon its cylindrical face, said roller also having means for positively advancing said can end in a straight line of travel while the scoring operation takes place.

35 6. In a machine for scoring can ends, the combination of a pair of rollers between which the can ends may be passed, said rollers being mounted to rotate about axes located in the same horizontal plane, one of said rollers carrying a scoring die, and means for feeding can ends between said rollers.

40 7. In a machine for scoring can ends, the combination of a pair of rollers between which the can ends may be passed, said rollers being mounted to rotate about axes located in the same horizontal plane, one of said rollers carrying a scoring die the edge of which defines the exact shape and dimension of the part to be removed from a can end.

45 8. In a machine for scoring can ends and the like, the combination of cooperating rollers, one of said rollers being provided with a scoring die, a movable mounting for said scoring roller and a spring urging said mounting and the roller carried by it to its work in the scoring operation.

50 9. A machine for scoring can ends and the like, the combination of a pair of rollers one of which has scoring means, which rollers are adapted to advance and score the sub-

ject article, means for arranging a subject article adjacent said rollers, and a device carried by a said roller for engaging said article in timed relation with the rotation of the scoring means of said rollers for moving it between the rollers to accomplish a scoring operation.

55 10. In a can end scoring machine, the combination of a scoring roller provided with a scoring die for scoring action, a backing roller cooperating with the scoring roller to advance the can end during the scoring operation, a said roller having a projection adapted to engage a part of the can end to positively insert it between said rollers.

60 11. In a can end scoring machine, the combination of a scoring roller provided with a scoring die for scoring action, a backing roller cooperating with the scoring roller to advance the can end during the scoring operation, a said roller having a projection adapted to engage a part of the can end to positively insert it between said rollers and in predetermined relation to said scoring die.

65 12. In a can end scoring machine, a scoring roller having upon its face a scoring edge defining the outline of the desired removable part of the can end, and combined therewith an opposing smooth anvil roller having all of its operative surface maintained spaced 70 away from said scoring edge during the scoring action of said rollers.
